E. L. OGLE

ELECTRIC FUSE

Filed Oct. 31, 1921

Inventor
Elmer L. Ogle
by Elmer L. Ogle

UNITED STATES PATENT OFFICE.

ELMER L. OGLE, OF CHICAGO, ILLINOIS, ASSIGNOR TO FEDERAL ELECTRIC COMPANY, OF CHICAGO, ILLINOIS, A CORPORATION OF ILLINOIS.

ELECTRIC FUSE.

Application filed October 31, 1921. Serial No. 511,862.

To all whom it may concern:

Be it known that I, ELMER L. OGLE, a citizen of the United States, and a resident of Chicago, county of Cook, and State of Illinois, have invented certain new and useful Improvements in Electric Fuses; and I hereby declare that the following is a full, clear, and exact description thereof, reference being had to the accompanying drawings and 10 to the letters of reference marked thereon, which form a part of this specification.

This invention relates to overload circuit breakers, commonly known as fuses, adapted for use in multiphase circuits, and consists of the matters hereinafter described and more particularly pointed out in the appended claims.

The object of the invention is to improve and simplify the construction of a fuse of the kind; to reduce the cost of manufacture by making the parts easy to assemble, and in particular to standardize and improve the construction and arrangement of the heating coil, so that it may be produced as 20 a unit, complete and ready for insertion when assembling the parts of the cartridge.

Other novel features will be pointed out as I proceed with my specification.

In the drawings:

30 Figure 1 represents a longitudinal, central section through the improved fuse;

Figure 2 is another longitudinal, central section in a plane at right angles to that of the previous section, as indicated by the line 35 2—2 of Figure 1;

Figure 3 is a cross-section through the fuse in a plane indicated by the line 3—3 of Figure 1;

Figure 4 is a perspective view of the novel 40 heating coil unit as it appears when ready for insertion in the cartridge;

Figures 5 and 6 are detail perspective views of parts to be more particularly described later.

45 Figure 7 is a perspective view of a stud used in the construction.

Referring now to that embodiment of the invention illustrated in the drawings:—The fuse comprises a body 10 of insulation material, as fibre or the like, with metallic heads 11, 12, each carrying a blade contact

11^a, 12^a and an enclosed cartridge 13 containing fusible bars 14 (two as shown) and a heating coil unit 15 with terminals 16, 16

connected to spring contacts 17, 17 on the 55 outside of the cartridge body. The construction in these respects, save for the heating coil unit itself, is substantially as disclosed in an application filed by me on August 29, 1921, Serial Number 496,207, and 60 as the details of said construction form no part of the present invention, they need not be more particularly described here.

The heating coil unit 17 consists of a narrow, elongated core 18, comprising two outer sheets 19, 19 of asbestos, or like fireproof material, and an intermediate sheet 20 of mica; of a coil of resistance wire 21 of the required length, wound upon said core 18; and of two sheets 22, 22 of mica of substantially 70 the same length as, but wider than the core, so that they project beyond each side of the core and beyond the coil wound thereon,—the several sheets being securely attached together by means of metal rivets, which extend through the five thicknesses of material at or near the ends of the unit, as clearly shown in Figure 4. The ends of the resistance wire are extended beyond the edges 75 of the mica sheets 22, to provide the terminals 16, 16, which extend through the cartridge wall and are connected to the spring contacts 17, as shown and as described in my application hereinbefore referred to.

In assembling the cartridge, the heating 80 coil unit 15 is inserted into the cartridge and placed in a position adjacent to and parallel to the fusible bar or bars 14, and preferably between said bars as shown, when two such bars are used. A tube of asbestos 85 25 is inserted within the cartridge body in advance of the insertion of the heating unit and the heating unit, which is made somewhat narrower than the inner diameter of the cartridge body, is held in place by reason of the engagement of its lateral edges against the somewhat yielding inner surface of the asbestos tube. The powder in the cartridge also packs against the outer faces of the heating unit, and acts to lock 90 it in its proper position within the tube. The advantage and readiness of assembly of a cartridge in which is used the improved heating unit, will be manifest to those familiar with the art.

100 The use of the core 18 with the resistance wire 21 coiled about it, makes it possible to bring a greater length of resistance wire

within the comparatively small limits of the unit. The outer mica plates or sheets 22, extending as they do, beyond the sides of the core, fully insulate the coil electrically 5 and in addition act, when the coil is heated by current passing through it, to confine and direct the heat waves into the space between the projecting edges of said plates, so that the heat is concentrated at the lateral 10 edges of the unit to act with more effect than if scattered and diffused in all directions from the coil.

The improved fuse is provided with the following novel devices for connecting to 15 the fuse body the wires by means of which its heating coil 21 is connected to another circuit. (See Figures 3, 5 and 7.) 23 indicates a pin or stud provided with a radial flange 24 intermediate its ends. The bottom 20 tom end part 25 is threaded below the flange and the body 10 of the fuse is tapped to receive said part 25, which projects inwardly beyond the wall of the fuse body in position to engage one of the spring contacts 17 on 25 the cartridge 13. A thimble 26 made of insulation material (shown in perspective in Figure 5) is engaged upon the stud 23 and between its flange 24 and the fuse body 10. Said thimble has an apertured bottom wall 30 27, flat on the inside for engagement with said stud flange and curved on the outside as indicated at 28 to fit the surface of the fuse body. Thus when the stud is inserted through the aperture in the bottom wall 27 35 of the thimble and screwed home into the fuse body, the thimble is securely fixed to the fuse body. The upright side walls 29, 29 of the thimble are divided by diametrically opposite slots 30, 30. 40 The end part 31 of the stud above the flange 24 is somewhat reduced in diameter and is threaded to receive a thumb-nut or cap 32 consisting of a tubular, inverted cup 33, constituting a head, of hard rubber or 45 other suitable insulating material and of an internally threaded metal sleeve 34, fixed within said cup. The thumb-nut is made of a diameter to fit easily within the upright side walls 29 of the thimble. 35 indicates a 50 washer which is engaged on the stud 23, next above its flange 24. An end 36 of the wire leading to another circuit is looped about the stud 23, in the space between the flange 24 and the washer 35, whereupon the thumb-nut 55 is screwed down to securely grip the said loop between the washer and the flange. The thimble 26 extends considerably above the base of the thumb-nut, when the thumb-nut is screwed home, as clearly shown in 60 Figure 1. Two devices of the kind are provided on each fuse body, as shown in Figure 1.

Each insulation thimble 26, by means of its upright walls 29, presents a barrier or 65 shield to prevent arcing in the gap between

the terminal connection of the wire 36 and the proximate metallic head of the fuse. It also prevents the possibility of a short circuit between said terminal connection and head by means of a tool, as a screw driver, 70 when carelessly dropped in position to bridge said gap.

In order to adapt the fuse for use without the necessity of providing extra terminals in the line circuit in which the fuse 75 is placed for the wires leading to the heating coil of a fuse in another circuit, the fuse heads 11, 12, are preferably each provided with a screw 37 and washer 38,—the latter having diametrically disposed upstanding 80 lugs 39 which embrace the sides of the screw head and retain the wire terminal end in a familiar manner. The screws are threaded through the tubular parts of the heads into the fuse body and are located in the 85 diametric plane of the blades 11^a, 12^a, as shown in Fig. 1. This construction permits the use of a screw and a single washer instead of a screw and two washers as in my earlier application filed August 29, 1921, 90 Serial Number 496,207.

I claim as my invention:—

1. In combination with the tubular body of a fuse cartridge having a plurality of terminals in the wall thereof, a fusible element in said body comprising two longitudinally extending, spaced parallel bars, a heating element arranged between said fusible bars and comprising a core of insulation material, a heating coil of wire wound upon said core with its ends attached to said terminals, plates of insulation material between which said core is engaged and held, said plates projecting at both sides beyond said core to engage the interior part of said tubular body so as to be held in position thereby, and means for attaching said plates and core together at points beyond the end loops of the heating coil. 105

2. In combination with the tubular body 110 of a fuse cartridge having a plurality of terminals in the wall thereof, an asbestos tube fitting the interior of said body, a fusible element in said body comprising two longitudinally extending, spaced parallel 115 bars, a heating element arranged between said fusible bars, and comprising a flat core of mica with an asbestos sheet on each side thereof, a heating coil of wire wound upon said core with its ends attached to said terminals, plates of mica one on each side of said core, said plates projecting at both edges beyond said core and engaging said asbestos tube so as to be held in position thereby, and rivets for attaching said plates and core together at their ends. 120

3. A heating unit for electrical fuse cartridges, comprising a comparative long, narrow core of insulation material consisting of two sheets of asbestos and an intermediate 125

sheet of mica, a coil wound on said core, mica plates of substantially the length of, but wider than said core, embracing said core between them, with their lateral edges projecting at each side beyond said core, and rivets for attaching said several plates and sheets together at their ends.

In testimony that I claim the foregoing as my invention, I affix my signature, this 13

day of October, A. D. 1921.

ELMER L. OGLE.
